CLAIM

The ornamental design for a cosmetic applicator, as shown and described.

DESCRIPTION

FIG. 1 is a perspective view of a cosmetic applicator showing the claimed design;

FIG. 2 is a front view thereof;

FIG. 3 is a back view thereof;

FIG. 4 is a left view thereof;

FIG. 5 is a right view thereof;

FIG. 6 is a top view thereof; and,

FIG. 7 is a bottom view thereof.

The broken lines in the figures show portions of the cosmetic applicator that form no part of the claimed design.
